[57] CLAIM

The ornamental design for a tree stump puller, as shown and described.

DESCRIPTION

FIG. 1 is a front elevational view of the tree stump puller showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.

The undisclosed remaining portion of the rope is conventional in appearance. The rope has also been shown broken away to indicate indeterminate length.

The broken line showing of a tree stump is for illustrative purposes only and forms no part of the claimed design.
